UNITED STATES PATENT OFFICE.

FRITZ LESCHINSKI, OF PHILADELPHIA, PENNSYLVANIA.

COAL-CHUTE.

No. 889,023.

Specification of Letters Patent.

Patented May 26, 1908.

Application filed June 18, 1907. Serial No. 379,583.

To all whom it may concern:

Be it known that I, FRITZ LESCHINSKI, a citizen of the United States of America, residing at Philadelphia, in the county of 5 Philadelphia and State of Pennsylvania, have invented new and useful Improvements in Coal-Chutes, of which the following is a specification.

This invention relates to coal chutes, and 10 one of the principal objects of the same is to provide means whereby the chute may be swung at right angles to the wagon or at any required angle to the wagon.

Another object of the invention is to provide means for connecting a chute to a wagon and properly supporting it in position under a discharge gate in position to discharge the coal at any angle required from the point of discharge in the wagon 20 box.

These and other objects may be attained by means of the construction illustrated in the accompanying drawings, in which:

Figure 1 is a perspective view of a coal 25 wagon provided with my improvement. Fig. 2 is a detail sectional view showing the coal chute adjusted for discharging coal at right angles to the wagon body. Fig. 3 is a similar view showing the coal chute adjusted for discharging coal in line with the 30 wagon body. Fig. 4 is a detail plan view of the chute adjusting lever. Fig. 5 is a side elevation of the same. Fig. 6 is a detail plan view of one end of the reach. Fig. 7 is a detail sectional view of the reach and showing the manner of mounting the sliding pivot 35 pin thereon.

Referring to the drawing for a more particular description of my invention, the 40 numeral 1 designates the box of a coal wagon to which is pivotally connected a series of elevating levers 2 which are connected to the running gear 3 of a wagon. Any suitable means for elevating the box 1 may be used, 45 and since this mechanism forms no part of the present invention, it has not been shown.

At the rear end of the wagon box 1 a discharge outlet 4 is provided, and a hood 5 is connected to the rear end 6 of the box 1. A 50 sliding door 7 closes the opening 4 and is provided with a lever 8 pivoted at 9 to a bracket 10, said lever having a handle 11 by means of which the sliding door 7 may be opened and closed. A reach bar 12 is supported under the front end of the box 1 by 55 means of a bracket 13 and a supporting

block 14. The rear end of the reach 12 is provided with a vertical flange 15 supported upon a U-shaped bracket 16 secured underneath the box 1. The rear end of the reach 60 12 is reduced in width, as at 17, and provided with a slot 18 in its outer end. A lever 19 provided with spaced lugs 20 is pivoted upon a pin 21 extending through said lugs and through the reduced portion 17 65 of the reach 12. The lever 19 is provided with a suitable handle 22 and depending from the lower side of the lever is a curved perforated sustaining member 23 which is adapted to pass through the slot 18 in the 70 reach 12 and to be held in adjusted position by means of the removable pin 24 which extends through any one of the perforations 25 to hold said lever at any required angle relatively to the reach 12. Mounted upon the 75 lever 19 is a slide 26 having inwardly extending flanges 27 which engage the underside of the lever 19, said slide having an upwardly projecting pivot pin 28. The discharge chute 29 has secured thereto underneath the upper 80 end thereof a keeper 30 provided with a recess 31 and a slot 32 in the lower wall thereof through which slot projects the pivot pin 28 and fitted to the end of said pin is a nut or washer 33, as shown more particularly in 85 Fig. 3.

The operation of my invention may be briefly described as follows: When it is desired to discharge the coal in line with the wagon box 1, the lever 19 is swung down to rest 90 upon the end of the reach 12, as shown in Fig. 3. Should it be required to discharge the coal at an angle to the box 1 the lever 19 is raised, and the pin 24 is inserted in one of the slots 25 of the curved bar 23. Should 95 it be required to adjust the chute 29 at right angles to the box 1, the lever 19 is adjusted to the position shown in Fig. 2 of the drawing and the sliding door 7 is then operated to permit the coal to be discharged into the 100 chute 29, as will be understood.

From the foregoing it will be obvious that a coal chute made in accordance with my invention and mounted as described, can be readily adjusted to discharge the coal at any 105 angle from the wagon box. It is desirable to discharge the coal at right angles to the wagon box for the reason that this permits the wagon to be driven up to the side of the curb entirely out of the way of passing teams. 110

My invention is comparatively simple in construction, is quick in operation, and can

be manufactured at comparatively slight cost.

Having thus described the invention, what I claim is:

- 5 In a device of the character described the combination of a wagon box having an opening in the rear end thereof and a sliding door for closing said opening, a reach supported under the wagon box, a lever pivoted to said
- 10 reach, a slide mounted on said lever and

provided with a pivot pin, a chute pivotally mounted on said pin and a curved sustaining member for supporting said lever at different angles from said reach.

In testimony whereof I affix my signature 15 in the presence of two witnesses.

FRITZ LESCHINSKI.

Witnesses:

ERNEST NELSON,
JOHN PETERSON.
